UNITED STATES PATENT OFFICE.

HN F. MARTIN, OF CERESCO, AND JULIUS W. ORTON, OF COLDWATER, MICHIGAN.

DESIGN FOR A CARPET-STRETCHER PLATE.

SPECIFICATION forming part of Design No. 28,943, dated June 28, 1898.

Application filed May 31, 1898. Serial No. 682,215. Term of patent 14 years.

all whom it may concern:

Be it known that we, JOHN F. MARTIN, residing at Ceresco, in the county of Calhoun, and JULIUS W. ORTON, residing in the town of Coldwater, (Hodunk P. O.,) in the city of Branch, State of Michigan, citizens of the United States, have invented a new and original Design for a Carpet-Stretcher Plate, which the following is a specification.

This invention relates to a new and original design for a carpet-stretcher plate; and it has as its object to provide a design of this character which shall be both useful and ornamental.

The leading feature of the design resides in a rectangular plate provided on one face thereof with parallel transverse rows of tapering spur projections disposed obliquely in the same direction and with oblong openings alternating with the transverse rows of projections.

The minor features of the design are having the obliquely-disposed spur projections rounded or conical form, the oblong openings next to the ends of the plate formed with inwardly-projecting lobes at their ends, and the remaining oblong openings formed in a substantially elliptical shape.

In the drawings, Figure 1 is a perspective view of a carpet-stretcher plate embodying the herein-described design. Fig. 2 is a plan

view thereof. Fig. 3 is a cross-sectional view on the line 3 3 of Fig. 2.

Referring to the drawings, the numeral 1 designates a flat rectangular skeleton plate, 35 provided on one face thereof with parallel transverse rows of tapering spur projections 2. The spur projections 2 of each transverse row thereof are disposed obliquely in the same direction and are of a rounded or conical form, 40 and in the spaces intervening between the transverse rows of teeth the plate 1 is provided with oblong openings 3. All of the oblong openings 3, excepting those next to the ends of the plate, are of an approximately 45 elliptical shape, while said openings next to the ends of the plate are bounded at their ends by inwardly-projected lobes 4, forming an integral part of the plate.

What we claim is—

The design for the carpet-stretcher plate herein shown and described.

In testimony that we claim the foregoing as our own we have hereto affixed our signatures in the presence of two witnesses.

his
JOHN F. X. MARTIN.
